United States Patent Office

Des. 201,736
Patented July 20, 1965

201,736

TOASTER

Jerold R. Peterson, Roselle, Ill., assignor to Sunbeam
Corporation, Chicago, Ill., a corporation of Illinois

Filed July 9, 1963, Ser. No. 75,723

Term of patent 14 years

(Cl. D81—10)

Fig. 2.

Fig. 3.

Fig. 4.

Fig. 5.

Fig. 6.

FIG. 1 is a right side perspective view of a toaster embodying my new design;

FIGS. 2 and 3 are front and rear elevational views thereof, respectively;

FIG. 4 is a top plan view thereof;

FIG. 5 is a left side elevational view thereof; and

FIG. 6 is a fragmentary sectional view taken along line 6-6 of FIG. 2, it is to be understood that the pattern of ribs continue uniformly throughout the broken line area.

The essential features of my design reside in those portions shown in full lines.

I claim:

The ornamental design for a toaster, as shown and described.
